AUTOMATIC PLUG MAKING MACHINE

William Scott Whiting, Jr., Canton, N. C.

Application July 27, 1937, Serial No. 155,997

3 Claims. (Cl. 144—46)

This invention relates to woodworking machines or the like and has reference more particularly to machines of this type which are adapted to perform a plurality of operations on a piece of stock or blank and to properly support and manipulate the blank during said operations.

The general object of the invention is to provide a novel and improved machine of this character which is automatic in operation, requiring a minimum of supervision or attention; and which is easy and economical to construct, install, operate, and maintain.

A more particular object of the invention is the provision, in a device of this kind, of a plurality of cooperating instrumentalities designed to perform certain sequential and simultaneous operations on the stock and adapted to automatically start and stop said operations at timed intervals along a complete cycle during which the blank stock is converted into a finished article.

Another object is the provision of novel automatically operative means for seizing the stock and, after the effecting of a preliminary operation thereon, transporting the blank, and releasing it to the control of another instrumentality for the effecting of further operations thereon.

A further object of the invention is to provide in such a machine a novel self-centering, resilient, gripping blank transferring member adapted to present pieces of stock of non-uniform dimensions and contour to the centers of a turning unit or lathe member in proper position for reception by said centers, and also adapted to automatically yield the blank to the control of said centers upon retraction of the transfer member.

A further object is the provision of novel driving and operating means for the machine, whereby the various transferring, gripping, shaping, and releasing members may be actuated in their proper relation and sequence to convert the raw stock or blank into the finished article desired.

The invention in its preferred embodiment contemplates the provision of a paper-roll plug forming machine of the properties described, but it is obvious that within its broader aspects it may embrace spool or bobbin making machines or similar devices which involve the severing of a blank from a piece of stock and shaping it by turning, drilling, or other operations.

In such preferred form—for example, as illustrated in the accompanying drawings and described in the present specification—the machine, supported by a suitable frame, comprises a blank supporting and transferring clamp, which receives one end of a piece of roughly round or

polygonal stock while a cut-off member advances, severs a blank of the required length from the stock, and then returns to its initial position. The clamp then carries the severed blank from its original position to a second station where it is met by an oscillating lathe member which grips the blank and automatically withdraws it from the clamp which then returns to its initial position to receive the blank for the preparation of the subsequent article. The lathe member carries the blank forwardly upon its return movement, and during this movement the blank is drilled, a roughing cut is taken from its outer surface and finally a finishing cut is effected and the plug released.

Intermittent rotation of the live center of the lathe member is provided for by certain tensioning and braking means which also comprise novel features of the invention.

Other objects and features of novelty will be apparent from the following specification when read in connection with the accompanying drawings, in which—

Figure 1 is a plan view of a machine which embodies the principles of the invention;

Figure 2 is a vertical longitudinal sectional view of the device shown in Figure 1 and taken on line 3—3 of that figure;

Figure 3 is a view in transverse vertical section taken substantially on line 3—3 of Figure 1;

Figure 4 is a fragmentary view in elevation of the combination drill, lathe, and transfer member of the machine;

Figure 5 is a fragmentary plan view of a portion of one side of the machine showing the lathe center actuating cam and connecting linkage;

Figures 6 and 7 are somewhat diagrammatic views in side elevation of the lathe driving gearing;

Figure 8 is a view in side elevation of the lathe oscillating cam;

Figure 9 is an enlarged fragmentary longitudinal sectional view taken substantially on line 3—3 of Figure 1, similar to Figure 3, and showing the positions of the parts when the blank is being transferred from the clamp member to the lathe member.

Figure 10 is a fragmentary vertical sectional view of the drill operating cam and connecting arm; and

Figure 11 is a chart indicating graphically the timing of the various operations of the machine effected by means of the several cam members.

For effecting the described objects of the present invention, the illustrated embodiment com-

prises a plurality of woodworking tools or instrumentalities adapted to properly shape the plug or spool to be formed. Three instrumentalities include a cut-off tool preferably comprising a rotary saw which is adapted to oscillate to and from the initial position of the stock; a lathe member which is also oscillatably mounted in the machine and is provided with a drill concentric with the centers thereof for boring a hole through the blank; a rotating roughing tool for initially shaping the periphery of the blank and a final finishing tool for smoothing the surface thereof.

A substantially rectangular supporting frame is provided for the machine and, as shown more clearly in Figures 1 and 2 of the drawings, comprises the front frame member 10, rear frame member 11, and side members 12 and 13. A number of transverse shafts extend between the side frames 12 and 13 for purposes which will be described in detail at the proper points. These shafts include the drive shaft 15 which receives power from a suitable source through the belt pulley 16; the saw supporting shaft 18; the shaft 20 which pivotally supports a blank transferring arm; the hollow shaft 22, which supports the swinging lathe member; and the cam shaft 25 upon which are fixed the cams for actuating the operative members in their proper sequence.

The first operation performed by the machine is that of severing a blank from a piece of rough stock, which may be of varying diameters and contour and may comprise round or polygonal stock, tree limbs, cord wood, or billets of various cross-sectional shapes. A piece of stock of suitable length is placed in a suitable receptacle exemplified by the rack or trough indicated somewhat diagrammatically at 28 in Figure 1 with its forward end extending for a distance beyond the ends of the trough approximating the desired length of the finished article.

The cut-off member comprises, in this instance, the circular saw 30 which is fixed to the end of the shaft or axle 31 which rotates in the outer portion 32 of the pivoted saw frame member indicated generally by the numeral 33. This frame member has an inner sleeve portion 34 which rotates upon the saw shaft 18. A pulley 35 is secured to one end of the axle 31, and is adapted to be driven by means of the belt 36 from the drive pulley 37 secured to the power shaft 15. The saw frame 33 is provided with a cam arm 38 which projects from the lower portion 34 of the frame and carries the roller 39 which contacts with the cam 40 secured to the cam shaft 25 and so shaped as to oscillate the saw frame 33 to and from the positions indicated at A and B in Figure 3 of the drawings; the position A being the initial position of the saw, and the position B being the final position after it has severed a blank indicated at 100 from the piece of stock. It will be noted from Figure 3 that the saw shaft 18 is directly above the driving shaft 15 and the arc of oscillation of the saw frame is not so wide as to substantially disturb the tautness of the belt 36 which passes around the pulleys 35 and 37, during oscillatory movement of the saw.

For holding the blank during its severance from the piece of stock carried in the rack 28, and for transferring it from this initial cut-off position, designated by the numeral I, to the next station in its progress through the machine, there is provided a transfer member designated generally by the reference numeral 45. This member comprises the arm 46 which is provided with a sleeve 47 whereby it is pivotally mounted

upon the shaft 20. The outer end of the arm 46 is rigid with the hollow tubular shank portion 48 of the transfer member which extends at an acute angle with the arm 46. The transverse rod 50 extends from each side of the shank 48 at its outer end and serves to guide the short sleeve members 51 which carry the angular jaws 52 which serve to releasably clamp the blank 100 during its transfer from the cut-off position to the subsequent positions. Washers 53 secured to the ends of the shaft 50 serve as abutments for the coil springs 55 which surround the ends of the shaft 50 and are compressed between these abutments and the jaws 52, whereby the jaws are continually urged inwardly toward each other so as to resiliently clamp work of various cross-sectional dimensions. In order to prevent rocking movement of the jaws longitudinally of the blank, guide rods 57 extend from the shank 48 through openings formed in the rear ends of the jaw members 52.

Pivoted to each of the jaw members 52 at intermediate points are the ends of the short toggle levers 58; the opposite ends of these levers being pivotally secured as at 59 to the trigger or actuating rod 60 which is adapted to reciprocate within the tubular shank 48 of the transfer member. A slot 61 is formed in this shank for the accommodation of the pivot element 59 which joins the toggle levers 58 to the element 60. The jaws 52 are formed with substantially concave inwardly directed faces, the preferred form being illustrated as angular, whereby the points of contact with the various non-uniform pieces of stock may be a minimum, and whereby the stock of no matter what cross-section may be properly centered for presentation to the lathe member, which will presently be described. It will be noted that the lower jaw 52 is hinged as at 54 and the outer portion thereof is provided with an arcuate spring guiding rod 56 which passes through an opening in the inner portion of the jaw. A coil spring 62 surrounds the rod and is adapted to be compressed between the inner and outer sections when the lower jaw members moves downwardly to permit the release of the blank. The spring 62 is of sufficient strength as compared with the springs 55 so that the centering function of the latter springs is not impaired. It will thus be seen that the transfer member 45 provides resilient, releasable, self-centering, gripping means for the blank.

A cam arm 63 extends inwardly from the sleeve 47 of the transfer member 45 and is provided with the cam roller 64 which contacts with the cam 65 carried upon the cam shaft 25 and so shaped as to swing the transfer member 45 to and from its initial position indicated in Figure 3 to its delivery position indicated in Figures 1 and 9 of the drawings.

The lathe member for receiving the blank 100 from the transfer member 45 and for cooperating with the cutting tools to shape the blank, will now be described. The lathe member designated generally by the reference numeral 70 is shown to the best advantage in Figure 4 of the drawings, and comprises the head stock 71 and the tail stock 72, the former being provided with the sleeve or collar 73 secured to the rotatable hollow lathe shaft 22 for a swinging movement about the axis of this shaft. The tail stock 72 is provided with a similar collar 74 which is suitably keyed to the hollow shaft 22 and preferably adjustable longitudinally thereon by suitable means not shown for the accommodation

of blanks of various lengths. The head and tail stocks are connected with their respective sleeves or collars by the webs or plates 75 and 76 respectively. Extending downwardly from the hollow lathe supporting shaft 22, or from one or the other of the collars 73 or 74, is an arm 16' which is pivotally connected with one end of the cam link 78, as by means of the adjustable pin and slot connection 79. A lathe oscillating cam 80 is carried by the cam shaft 25 and serves to reciprocate the link 78 by its contact with the cam roller 82 which is preferably anti-frictionally mounted at one end of the bifurcated frame 83 which straddles the cam 80 and is provided with slots 84 for the accommodation of the cam shaft 25 during the oscillatory movement of the linkages 78, 83. These features are clearly shown in Figures 1, 7 and 8 of the drawings.

Referring again more particularly to Figure 4 of the drawings, it will be observed that the annular tail center 87 of the lathe is rotatably mounted by means of the anti-friction bearing 88 upon the end of the shaft 89 which passes through the tail stock 72. Thus, by reciprocation of the shaft 89 the tail center 87 may be moved to and from the live center 90, rotatably carried by the head stock 71, in order to positively clamp the blank 100 between these centers. The reciprocation of the tail center 87 is by means of the following connections. A lever 92 is fulcrumed adjacent its mid-portion to the bar 93 which is secured as at 94 to the web 76. A coil spring 95 connects the lower portion of the lever 92 with the web 76 and serves to urge the tail center 87 outwardly away from the live center 90. The lower end of the lever 92 passes through the slot 97 in the hollow shaft 22 and is pivotally and adjustably connected as at 98 with the reciprocating shaft 101 which passes axially through the hollow shaft 22, and whose outer end is connected with cam means for actuation and release of the blank by the lathe centers, all as clearly shown in Figure 5 of the drawings.

The outer end of the shaft 101 is threaded as at 102 for the adjustable reception of the flanged internally threaded sleeve 103 which is provided with the wheel 104 for manual rotation. The forked end 105 of the cam lever 106 is received between the flanges of the sleeve 103 for pivotally connecting the shaft 101 with the cam actuated rod 108. The latter rod is fulcrumed to the bracket 107 carried by the frame member 13 of the machine, and the opposite end thereof is provided with the cam roller 108 which contacts with the effective face 109 of the cam disc 110 which is carried on the projecting end of the cam shaft 25 exteriorly of the frame 13. The face 109 of the cam 110 is provided with the depressed portion 111 into which the roller 108 drops when it is desired to release the blank from between the centers 87 and 90. The roller 108 rides up the inclined portion of the cam face 109 at the proper point in its cycle of movement in order to clamp the centers upon the next succeeding blank.

By these means the pivoted lathe member 70 is caused to oscillate between the positions indicated at II and III in Figure 3 of the drawings. At the position designated II the lathe member 70 is adapted to meet the transfer member 45 for the exchange of the blank 100, and these coincident positions are shown in Figure 9 of the drawings. In this position the cam 110 causes the lathe centers 87 and 90 to positively

grip the blank 100 which has been properly centered for them by means of the novel self-centering transfer member 45. Under the influence of the cam 65 the transfer member 45 is caused to return from position II toward its initial position I, and the jaws 52 move apart automatically against the influence of the springs 50 and snap away from the blank leaving it in the possession of the lathe member 70. The transfer member 45, upon its return to the initial position I, approaches the abutment 115 against which the projecting end of the trigger or jaw actuating rod 60 strikes. Continued movement of the arm toward the abutment serves to open the jaws 52 from the dotted line position in Figure 3 to the full line position for the reception of the next succeeding blank to be cut from the stock by means of the saw 39.

As the transfer arm 45 returns from position II toward position I, the lathe member 70 moves from position II toward position III, and shortly after leaving position II the live center begins to rotate the blank 100 preparatory to being acted upon by the cutters and drill. For rotating the live center the following mechanism is provided. Upon the outer end of the live center shaft 120 is provided the pulley 121 about which is trained a belt or chain 122. The lower turn of the belt 122 passes around the pulley 123 carried upon the drive shaft 15 as clearly shown in Figures 2, 6, and 7 of the drawings. In order to provide the proper tautness of the belt 122 during the time when the lathe is swinging from point II to the point III, and for preventing rotation of the lathe centers when the lathe is at the position II where it receives the blank, the following devices are provided. A pair of spaced discs 125, providing an idler carrying frame, are pivoted to the side frame as by means of the bracket 126. These discs are adapted to embrace the belt 122 and are secured together as by means of the pulley axles 127 upon which the small idler pulleys 128 are rotatably mounted. A coil spring 130 serves to connect the point 131 on the idler frame 125 with a point 131' on the lathe 20. When the lathe is in position III or approaching this position, the belt 122 is taut, passing around the idlers 128 as shown in Figure 7, and the spring 130 is placed under considerable tension and serves to urge the discs 125 in a clock-wise direction, thus tending to further taunt the belt 122.

When the lathe member is in the position II as indicated in Figure 6 of the drawings, the rotation of the live center of the lathe is prevented by the contact of the circular brake drum 132 carried upon the end of the live center shaft 120, with the stationary brake shoe 133 which is provided with a supporting bracket 134 secured to the main frame in any suitable manner, not shown. Just before the lathe member reaches the position designated by the numeral II, the clockwise rotation of the idler frame 125 is arrested by the contact of the abutment 124 carried by the idler frame with the stationary abutment 129 carried by the brake supporting bracket 134, as clearly shown in Figure 6 of the drawings. This permits the necessary slackness in the driving belt 122 to further prevent the rotation of the centers of the lathe during the seizing of the blank 100 from the transfer member 45. The rotation of the centers is permitted to resume after the brake drum 132 moves away from the brake shoe 133 and the tension of the belt 122 is restored by the separation of the stops 124.

and 129 and the influence of the tension spring 130.

During the movement of the lathe member 10 from position II to position III, the blank 100 is bored axially by means of the drill 135 which is disposed concentrically with the lathe centers 87 and 90, being mounted upon the inner end of a reciprocating shank 136 which passes through the head stock 71 of the lathe. A lever 137 is pivotally connected to the end of the shank 136 and to a fulcrum bar 138 attached as at 139 to the head stock web 75. Intermediate the ends of the lever 137 is pivotally attached the link 140 whose inner end is pivoted to one arm of the bell crank lever 141 fulcrumed at 142 to the plate 75. The free end 144 of the bell crank 141 projects beyond the inner margin of the plate 75 sufficiently to be contacted by the cam actuated lever or bar 145. As best shown in Figures 1 and 10 of the drawings, this rocking cam lever 145 is provided intermediate its length with a sleeve portion 146 which surrounds the shaft 20 upon which the lever is fulcrumed. The opposite end of the lever is provided with a cam roller 148, which rolls upon the surface of the cam 150 carried by the cam shaft 15. The cam 150 is so shaped as to cause the connecting linkage to feed the drill 135 through the blank 100 as it is being rotated by the live center 90. Suitable resilient means is provided for retracting the drill when the lever 145 is permitted to rock in the reverse direction due to the depressed portion of the cam 150. This means may comprise the coil spring 152 which may be placed around the drill shank 136 between the abutment 153 associated with the live center assembly adjacent the brake drum 132 and the corresponding abutment 154 carried by the shank 136. The cam 150 is timed so that the drill 135 passes through the blank and is retracted therefrom during the passage of the lathe member 10 from position II to position III. The tail center 87 is hollowed out as at 155 for the reception of the end of the drill 135 at the end of its working stroke.

During the movement of the lathe from position II to position III the blank 100 is brought past the rapidly rotating roughing tool 160 which is provided with the cutting blades 161 and is carried upon the end of the rotary shaft 162. This shaft is provided with bearings in the bracket 163 which is secured to the front side frame 10 as by means of the connections indicated at 165 in Figure 1. The bracket 163 may be vertically adjusted in any suitable manner, as for example by changing the relative position of the supports at 165. The outer end of the rotary shaft 162 is provided with the pulley 168 which is operatively connected with a drive pulley 169 as by means of the belt 170; the pulley 169 being carried by the drive shaft 15. After receiving the roughing cut which applies the general peripheral shape to the blank 100, the lathe member 10 proceeds to a point adjacent the position designated III where the finishing blade 175 trims the peripheral surface of the blank to the proper depth which may be regulated by a suitable feed effected by the hand crank 176, the blade and feed mechanism being carried by a suitable extension of the side frame 10. The plug or spool is now completed and may be released from the lathe member 10 at this point III or at any time during the return movement of the lathe to position II; or in fact, after it is returned to position II and before receiving the next blank from

the transfer member 45. The point at which the finished article is released will be determined, of course, by the relation of the lathe center actuating cam 110 to the lathe swinging cam 80.

One preferred manner of timing the operation of the several instrumentalities by the proper shaping and adjusting of the cams is indicated diagrammatically in Figure 11 of the drawings in which the points of change of the several appropriately designated cams are shown on the heavy lines indicating their movement. These critical points are indicated by the letters a, b, c, d, e, f, g, h, and i. The distance a-b represents the working stroke of the saw under the influence of its cam, and the interval b-c indicates the retracting stroke of the saw or cut-off member. It will be noted from the chart that during the interval c-d the transfer arm actuating cam is moving that arm from station I to station II, while at the same time the lathe swinging cam is moving the lathe member from station III to station II. The interval d-e represents the period when the transfer of the blank 100 from the arm 45 to the lathe 70 is taking place, these members, of course, being stationary at this point, and the lathe center cam operating to positively clamp the blank preparatory to being withdrawn from the transfer member 45. During the interval e-f the transfer arm is being brought back from station II to station I, thus releasing the blank, and the lathe member is starting upon its passage to station III, as indicated by the gradual slope of its representative line. Just beyond the point e and continuing to approximately the point g, the drill is being fed through the blank, and during the interval g-h the drill is being permitted to withdraw from the blank preparatory to releasing the centers, this releasing in this instance taking place during the interval i-a. During the relatively gradual movement of the lathe member from point e to point i, the roughing and finishing tools operate upon the blank while it is being rotated between the centers of the lathe. Of course, various modifications may be made in the synchronizing of these cams without departing from the scope of the invention, as for example, the blank need not be released nor need the drilling operation be entirely completed until the lathe member has returned to station II as indicated by the point d on the chart.

Suitable gearing 180 may be provided as indicated in Figure 2 of the drawings in order to connect the cam shaft 25 with the power shaft 15 for the proper actuation, the cam shaft 25, of course, rotating at a much slower speed than the drive shaft 15.

In some of the figures of drawing certain intervening portions of the mechanism are broken away or omitted entirely for the purpose of clarity of disclosure. Also, there are provided means for returning the various oscillating devices against cam pressure, such as for example, the springs 185 and 186.

It will be understood that various changes and modifications may be made in the embodiment illustrated herein without departing from the scope of the invention as defined by the following claims.

Having thus described the invention, what is claimed as new and desired to be secured by Letters Patent is:

1. In a woodworking machine of the class described, a supporting frame, a blank transferring

arm pivotally mounted on said frame, said arm comprising an angular shank, a pair of oppositely disposed inwardly concave jaws carried by the outer end of said shank, means mounting said jaws for bodily translatory movement toward and away from each other, resilient means for urging said jaws toward each other, a pair of toggle levers directly connecting said jaws, and a rod slidable along one portion of said angular shank, having a projecting end, and pivotally connected to both of said toggle levers at the mid-point of the toggle, and an abutment on said frame against which the projecting end of said rod is adapted to strike at one point during the movement of said arm, in order to actuate the toggle and spread said jaws apart.

2. In a machine of the class described, a blank feeding member comprising an arm, a transverse guide rod extending from each side of the said arm adjacent one end thereof, a pair of gripping jaws slidably mounted on said rod, one upon each side of said arm, spring abutments on each end of said rod, coil springs compressed between said abutments and said jaws respec-

tively, and toggle means for spreading said jaws against the pressure of said springs.

3. In a machine of the class described, a supporting frame, a blank feeding member movably supported upon said frame and comprising an arm, a transverse guide rod extending from each side of the said arm adjacent one end thereof, a pair of gripping jaws slidably mounted on said rod, one upon each side of said arm, 10 spring abutments on each end of said rod, coil springs compressed between said abutments and said jaws respectively, a pair of levers each having one of its ends pivotally connected with one of said jaws, said arm having a bore extending 15 at least partly therethrough, and a rod slidably disposed within said bore and pivotally connected with the other ends of said levers, thus forming a toggle, an abutment on said frame, one end of said rod projecting from said arm and adapted to strike said abutment at one point during the movement of said arm to reciprocate the rod, extend the toggle, and spread the jaws apart against the pressure of said springs.

WILLIAM SCOTT WHITING, JR.
